UNITED STATES PATENT OFFICE.

STEWART L. CAMPBELL, OF BERKELEY, AND JAMES J. SANTIAGO, OF LOS ANGELES,
CALIFORNIA, ASSIGNEES TO JOHN GRANT, OF LOS ANGELES, CALIFORNIA.

EXPANSIVE REAMER.

Original application filed February 1, 1928. Serial No. 250,963. Divided and this application filed
February 11, 1928. Serial No. 253,541.

This invention has to do with expansive cutting tools, reamers or underreamers. The particular design shown and explained herein is adapted specifically to rotary underreaming; but it will be recognized from what follows that, although the invention is particularly useful as a rotary tool, it is not necessarily restricted to such specific use.

In reamers where spring or similar actuation is used for expanding or protracting the cutters, it has been universally the case, so far as our knowledge goes, that the spring action, tending at all times to press the cutters outwardly, has caused them to "ride" 10 the casing while the tool is being lowered or pulled up through the casing. The drag of the cutters on the casing is, in many instances, quite forcible, particularly as the tool is being lowered; because the cutters are 15 usually expanded by some kind of wedging action, actuated by the spring, and the upward drag of the casing on the cutter accentuates the wedging action. The cutters thus, 20 in many instances, press outwardly with considerable force against the casing, cutting and scoring the casing, and causing considerable wear on the cutters.

It is the major object of this invention to provide a cutter locking or cutter holding 30 means which will hold the cutters inwardly in their collapsed positions; and to provide such a cutter holding or locking means, in a spring actuated expanding reamer, in such a manner that although the spring is available 35 for the performance of its usual cutter expanding function, the expanding action of the spring on the cutters is temporarily locked when so desired. Thus, in accordance with our invention as applied specifically to 40 an underreamer having a spring actuated expansion with wedging action, the expanding action of the spring is prevented when the cutters are contracted, so that there is then no acting force tending to press the cutters 45 out; and the spring pressure is, on the contrary, used for holding the cutters in their retracted or collapsed positions. In this present application we illustrate a mechanism 50 wherein the cutters are caused to expand by relative longitudinal movement—relative longitudinal movement as between the cutters or cutter carriers and the expanding mandrel. And in this present application the specific design involves the longitu-

dinal movement of the cutter carriers with 55 relation to the reamer body, the reamer body and expanding mandrel being stationary as related to each other; but the cutters moving longitudinally in the body is not a limitation on the broader aspects of the invention 60 as it is only the relative longitudinal movement between the cutters and mandrel that is involved in the invention.

For the purposes of specific description of the present embodiment, reference is had to 65 the accompanying drawings, in which—

Fig. 1 is a central longitudinal section showing the reamer in its contracted condition;

Fig. 2 is a similar view showing the 70 reamer in its expanded condition;

Fig. 3 is a cross-section on line 3—3 of Fig. 2;

Fig. 4 is a cross-section on line 4—4 of Fig. 1; 75

Fig. 5 is a cross-section on line 5—5 of Fig. 2;

Fig. 6 is a cross-section on line 6—6 of Fig. 1;

Fig. 7 is a detail section on line 7—7 of 80 Fig. 1.

In the drawings a suitable tubular body is shown at 10, having at its lower end the usual taper threaded box 11 to take the taper pin 12 of a drill bit 13 or of a sub which 85 connects to a drill bit below. The cutter expanding mandrel 14 which in this case is stationary with respect to the body, is centrally mounted in any suitable manner. For instance, it is shown as having a shouldered 90 enlargement 14^a over which a screw-threaded sleeve 15 is fitted, the sleeve screwing onto the body at 16. And the upper end of the mandrel has a taper-threaded pin 17 for connection with the usual drill stem, or with a 95 sub 18 which connects with the drill stem. The mandrel, so mounted, is longitudinally immovable with reference to the body, but it rotatable therein.

In the specific design here shown, the mandrel has a comparatively large upper part 14^b which is cylindric and fits the cylindric bore 10^a of the body so that the mandrel is given a good rotary bearing of some longitudinal extent, in the body. The lower part 105 of this large mandrel portion 14^b is provided with three shallow recesses or slots 14^c, which reach up from the level of the horizontal

shoulders 14^a located at the lower end of the large mandrel portion 14^b intermediate the slots 14^c. We mention the slots as being three in number, but merely because we choose here to show a reamer having three cutter carriers. Below shoulders 14^a the mandrel is reduced in size, as shown at 14^b; and a conical part 14^c leads between the reduced part 14^b and the slot bottoms at the level of shoulders 14^a, the upper end of the conical part being of the same diameter as the bottoms of slots 14^c. Fig. 2 shows this relationship.

The mandrel formation below the part 14^c—in fact, the whole formation of the mandrel in so far as it functions to cause expansion of the cutters—may be of any desired or preferred design. In the present instance there is shown simply a mandrel 20 having the tapered part 14^c and a tapered portion 14^b at its lower end. Cutter carriers 20 fit slidably in slot 21 through the body wall and have lateral wings 22 which bear outwardly against the inner wall surface to limit outward movement of the cutter carriers. The rear surfaces of the carriers are so formed that, by inter-action with the mandrel, they are forced outwardly to the expanded position shown in Figs. 2 and 3, 25 when they move upwardly in slots 21; and may move inwardly to the collapsed position shown in Figs. 1 and 4, when they are moved downwardly in the slots. This interaction of the carriers and mandrel will be well understood from a consideration of the drawing and needs no further explanation here. It is only of present interest that relative longitudinal motion between the mandrel and carriers causes expansion and contraction of the cutter carriers. The specific interformation of the carriers and mandrel, as here shown, is, in fact, not our specific invention, but the invention of John Grant, as set out in his application Serial 40 No. 254,266, filed February 14, 1928; our invention is in the application of our cutter-locking means to any cutter or cutter carrier that expands and contracts by relative longitudinal movement.

Below the cutter carriers is a cutter propeller 25, shown in the form of a cylindric sleeve which surrounds the mandrel extension 26 and is moved upwardly by the compression spring 27 housed in the lower part 45 of the body. Spring 27 also surrounds the mandrel extension of wash pipe 26. The lower end of the spring rests on a collar 28 which also surrounds the lower end of the wash pipe, the wash pipe and collar being supported by the tool joint pin 12. The wash pipe provides communication for circulating the water between the longitudinal circulation passage 30 in mandrel 14 and the circulation passage 31 of the drill bit. And 50 at the same time the wash pipe feeds the

circulating water into the lower body bore 32 in which spring 27 is housed. The lower end of pipe 26 fits loosely in collar 28 and merely rests upon the upper end of tool joint 12, and the water may find its way from the wash pipe 55 into chamber 32 thus from the lower end of the wash pipe. Or perforations such as indicated at 33 may be provided. To cause circulation of a certain amount of wash water through the spring chamber and also to points under the cutters, discharge passages 34 are provided under the cutters, the inner ends of these discharge passages being uncovered by the upward movement of propeller sleeve 25.

When the tool is put down through the well casing it is in the contracted condition shown in Figs. 1 and 4, the upper square shouldered end 35 of each cutter carrier being beneath the downwardly facing mandrel shoulder 14^a, and the mandrel recesses 14^c being out of register with the cutter carriers; the effect of spring 27 then merely being to press the cutter carriers up against this shoulder 14^a without any tendency of the spring to force the cutters outwardly to expanded position. In this position of the cutters they rest back against the smaller part of the mandrel; and, although they could be moved outwardly by a sufficient outward force, there are no such outward forces brought to play upon the cutters or cutter carriers in this contracted condition; or at least no outward forces of sufficient magnitude to move the cutters outwardly from their clamped positions. For, in the position of Fig. 1, it will be seen that the cutters are, in effect, clamped by the action of spring 27 between the cutter propeller 25 and the mandrel shoulders 14^a; and this clamping action is quite strong because of the strength of spring 27.

After the tool has been lowered through the casing, then the mandrel is rotated with reference to the body and cutters, the drag of the drill hole wall on the cutters or cutter being sufficient to hold the body from rotation while the mandrel is rotated within it. By rotation through approximately one-sixth of a revolution, the mandrel recesses 14^c are brought into register with the upper ends of the cutter carriers, and the spring immediately shoves the cutter carriers up to the position of Fig. 2, the upper inner parts of the carriers entering the mandrel recesses. In their upper movements the carriers are moved outwardly, due to the action of the conical mandrel part at 14^c upon which the diagonal carrier surface 20^a rides, and due also to the conical mandrel part at 14^b upon which the carrier face 20^b rides; so that the carriers reach their upper expanded positions as shown in Figs. 2 and 3. In this position the upper inner parts of the carriers fit snugly into the mandrel recesses 120

14°, as is indicated in Figs. 2 and 3; carrier wings 22 are pressed outwardly against the body wall, and the carriers all are interiorly backed up by the central mandrel. The 5 carriers in this position being thus fitted into both the body slots 21 and the mandrel recesses 14°; they form, in effect, a rotary driving connection between the mandrel and the body and carrier; so that upon continued 10 rotation of the mandrel the body and carriers are rotatively driven for reaming operations.

When it is desired to remove the reamer from the well it is only necessary to draw 15 it upwardly, when the upper projecting ends of the carriers will come into contact with the lower end of the well casing or shoe, the carriers being relatively moved downwardly toward the position of Fig. 1. At the same 20 time the carriers are passed inwardly by reason of engagement of the well casing or shoe with the diagonal faces 40; and they are thus moved down to near the relative elevation shown in Fig. 1, and are then moved 25 inwardly to the relative contracted position shown in Fig. 1.

In this contracted position of the cutters the tool may be removed upwardly through 30 the casing, even though the spring 27 is at all times tending to expand the cutters against the well casing. But this expansive action against the well casing can be obviated by merely rotating the mandrel again to the relative position shown in Figs. 1 and 35 4, throwing the shoulders 14° over the upper ends of the cutter carriers. The cutter carriers are then locked in their contracted positions just as they were when the tool was being lowered through the casing.

40 Locking the cutters against expansion for the purpose of removing them through the casing is not of so great importance as it is upon lowering the tool through the casing, because when the tool is being raised the 45 drag of the casing on the cutters tends at all times to force them down on the mandrel and force them further inwardly. But the tool is so constructed that the cutters can be locked in either situation. And, to provide for surety of locking action when the 50 tool is drawn up in the casing, each shoulder surface 14° may be given a slight diagonal corner cut 14° so that, even though engagement with the casing may not force 55 the cutter carriers clear down to the position of Fig. 1, rotation of the mandrel in a right-handed direction and the action of diagonal surfaces 14° on the upper ends of the carriers will force them through the slight 60 remaining distance down to the position of Fig. 1, so that the square shoulders 14° may pass over them to lock them. Likewise, and for the same purpose, the upper end of the carrier may have a diagonal corner surface 65 20°. It is only necessary to cut thus diagonal-

ally one corner of each square shoulder surface 14°, or of each carrier 20, as the mandrel can always be rotated in a right-handed direction; there being no necessity of ever rotating the mandrel left-handedly. 70

The cutter carriers 20 may be equipped with any suitable cutting elements or edges, and it is only for purposes of illustration we have shown the carriers equipped with roller cutters 45. The cutting elements may 75 be of any nature desired; for cutting or reaming in any kind of formation. Furthermore, the cutters may be of a nature to perforate or cut a well casing or pipe; the tool being particularly applicable for that purpose for 80 the reason that it is expanded by relative rotation of the mandrel within the cutters and contracted by relative longitudinal (upward) movement of the mandrel within the 85 cutters. The invention is thus not limited to expansive reamers but is applicable in general to expansive tools.

We claim:

1. In an expansive tool of the character described, a body and a cutter carrier movable laterally therein for expansion and contraction, a mandrel movable longitudinally and also rotatively with reference to the carrier, the mandrel and carrier being formed to cause lateral expansive movement of the 95 carrier by virtue of relative longitudinal movement in one direction, and the mandrel having a carrier receiving recess and an adjacent carrier engageable shoulder adapted 100 selectively to be registered with the carrier by relative rotation of the mandrel.

2. In an expansive tool of the character described, a body and a cutter carrier movable laterally therein for expansion and contraction, a mandrel movable longitudinally and also rotatively with reference to the carrier, the mandrel and carrier being formed to cause lateral expansive movement of the carrier by virtue of relative longitudinal movement in one direction, and the mandrel having a plurality of circumferentially spaced carrier receiving recesses and interspaced carrier engageable shoulders adapted selectively to be registered with the carrier by 110 relative rotation of the mandrel. 115

3. In an expansive tool of the character described, a body and a cutter carrier movable laterally therein for expansion and contraction, a mandrel rotatable within the body 120 and the mandrel and carrier being movable longitudinally relative to each other, the mandrel and carrier being formed to cause lateral expansive movement of the carrier by virtue of relative longitudinal movement in one direction, and the mandrel having a plurality of circumferentially spaced carrier receiving recesses, into which the carrier enters by said relative longitudinal movement, and a plurality of interspaced carrier engageable shoulders. 125 130

4. In an expansive tool of the character described, a substantially tubular body with a slotted wall, a cutter carrier movable longitudinally and radially in the wall slot, 5 yielding means tending to move said carrier longitudinally in one direction, a rotatable mandrel within the body, said mandrel having a wedge formation adapted to cause outward radial movement of the carrier upon 10 its longitudinal movement in said direction, and a carrier engageable shoulder on the mandrel having a limited circumferential extent so that rotation of the mandrel may throw said shoulder into and out of registration 15 with the longitudinal movement of the carrier.
5. In an expansive tool of the character described, a substantially tubular body with a slotted wall, a cutter carrier movable longitudinally and radially in the wall slot, 20 yielding means tending to move said carrier longitudinally in one direction, a rotatable mandrel within the body, said mandrel having a wedge formation adapted to cause outward radial movement of the carrier upon 25 its longitudinal movement in said direction, said mandrel having a plurality of circumferentially spaced and circumferentially extending shoulders adapted to prevent said longitudinal movement of the carrier.
6. In an expansive tool of the character described, a substantially tubular body with a slotted wall, a cutter carrier movable longitudinally and radially in the wall slot, 35 yielding means tending to move said carrier longitudinally in one direction, a rotatable mandrel within the body, said mandrel having a wedge formation adapted to cause outward radial movement of the carrier upon 40 its longitudinal movement in said direction, said mandrel having a plurality of circumferentially spaced and circumferentially extending shoulders adapted to prevent said longitudinal movement of the carrier, and 45 having interspaced longitudinally extending recesses into which the carrier may enter between adjacent shoulders.
7. In an expansive tool of the character described, a body and a cutter carrier movable laterally therein for expansion and contraction, a mandrel movable longitudinally and rotatively with reference to the carrier, the mandrel and carrier being formed to cause lateral expansive movement of the carrier by virtue of relative longitudinal movement in one direction, and the mandrel having a circumferentially extending shoulder of limited extent and adapted, by relative rotative movement of the mandrel, to be thrown into and out of registration with the 50 carrier.
8. In an expansive tool of the character described, a body and a cutter carrier movable laterally therein for expansion and contraction, a mandrel movable longitudinally and rotatively with reference to the carrier, the mandrel and carrier being formed to cause lateral expansive movement of the carrier by virtue of relative longitudinal movement in one direction, and the mandrel having a plurality of circumferentially spaced and circumferentially extending shoulders adapted to be thrown into and out of the longitudinal line of movement of the carrier by relative rotating movement of the mandrel. 55
9. In an expansive tool of the character described, a body and a cutter carrier movable laterally therein for expansion and contraction, a mandrel movable longitudinally and rotatively with reference to the carrier, the mandrel and carrier being formed to cause lateral expansive movement of the carrier by virtue of relative longitudinal movement in one direction, and the mandrel having circumferentially spaced carrier stopping and carrier receiving parts adapted selectively to be registered with the carrier by relative rotative movement of the mandrel. 60
